FIGURINE TOY OR THE LIKE

Robert H. C. M. Daenen, Erembodegem, Belgium, assignor to Dart Industries Inc., Los Angeles, Calif.

Filed Jan. 23, 1975, Ser. No. 543,588

Term of patent 14 years

Int. Cl. D21—01

U.S. Cl. D34—4 R

FIG. 1 is a top perspective view of a figurine toy or the like showing my new design;

FIG. 2 is a rear elevational view thereof;

FIG. 3 is a top plan view thereof;

FIG. 4 is a bottom plan view thereof;

FIG. 5 is a side elevational view thereof;

FIG. 6 is a front elevational view of another embodiment similar to that depicted in FIGS. 1-5; and

FIG. 7 is a top plan view of the embodiment shown in FIG. 6.

I claim:

The ornamental design for a figurine toy or the like, substantially as shown.
